UNITED STATES PATENT OFFICE

JOSEPH M. MAJEWSKI, JR., OF KANSAS CITY, MISSOURI, ASSIGNOR TO FOSTER L. TALGE, OF KANSAS CITY, MISSOURI, DOING BUSINESS AS RIVAL MANUFACTURING COMPANY

DESIGN FOR A FRUIT JUICER

Application filed November 21, 1932. Serial No. 46,100. Term of patent 14 years.

To all whom it may concern:

Be it known that I, JOSEPH M. MAJEWSKI, Jr., a citizen of the United States of America, residing at Kansas City, in the county of Jackson and State of Missouri, have invented a new, original, and ornamental Design for a Fruit Juicer, of which the following is a specification, reference being had to the accompanying drawing, forming part thereof.

Fig. 1 is a perspective view of my fruit juicer.

Fig. 2 is another perspective view of my fruit juicer.

I claim:

The ornamental design for a fruit juicer as shown.

In testimony whereof I affix my signature.

JOSEPH M. MAJEWSKI, JR.
